UNITED STATES PATENT OFFICE.

HUGH D. MURPHY, OF FORT WAYNE, INDIANA.

ELECTRICAL SIGNALING SYSTEM.

1,343,467.

Specification of Letters Patent. Patented June 15, 1920.

Application filed February 27, 1919. Serial No. 279,556.

To all whom it may concern:

Be it known that I, HUGH D. MURPHY, a citizen of the United States, residing at Fort Wayne, in the county of Allen and 5 State of Indiana, have invented new and useful Improvements in Electrical Signaling Systems, of which the following is a specification.

The invention relates to signaling systems 10 for railway grade crossings, block signals, gate operation, fire alarm and other electrical signaling uses. Its primary object is to provide a means of signaling which is simple, efficient, dependable and positive in 15 operation. It is adaptable to the various uses above set forth and in the present illustration of the invention it is shown as adapted to a railway grade-crossing signaling system.

20 In order to warn travelers at a highway grade crossing of a railway of an approaching train it is desirable that there shall be some signal visible or audible or both visible and audible which will attract the attention 25 of the traveler to the unsafe condition of the crossing. The natural method of attracting the attention of a traveler is by manually swinging a signal across the highway, the signal being illuminated for night use, 30 and an audible signal oftentimes accompanies the swinging of the signal. The object of my invention is to provide electrical and mechanical means by which a signal arm may be swung across the highway and 35 an audible alarm given, the devices being automatically set in motion or controlled by a passing train or railway vehicle.

Another object of the invention is to arrange the electrical circuits and mechanical 40 parts so that in case of failure in the operation of any part or circuit the signal will remain in the position of warning or danger. The signal is held in non-operated position by devices normally in a closed electrical circuit and said circuit is normally broken to 45 permit the signal to move to danger or warning position. Hence if said circuit is broken in any manner or current for any reason fails to flow through it the devices automatically place the signal in the danger or warning 50 position where it remains until repairs to the circuit or apparatus are made or current again flows through the circuit.

In the accompanying drawings I illustrate

an embodiment of the invention as applied 55 to a railway grade-crossing, in which—

Figure 1 is an adaptation of the invention to a double track railway; Fig. 2 an adaptation to a single track railway; Fig. 3 a plan view of the tripping switch, the cover 60 being removed; Fig. 4 a cross-section on line 4—4 of Fig. 3; Fig. 5 a plan view of the resetting switch, the cover being removed and Fig. 6 a cross-section on line A—A of Fig. 5; Fig. 7 a modified form of actuating lever 65 for the tripping or resetting switches; Fig. 8 a view similar to that of Fig. 1 illustrating more clearly the mechanical details of the various features and Fig. 9 a plan view of the holding magnet armatures, on line C—C 70 of Fig. 8.

Referring to the drawings, in which similar reference characters indicate like parts, and first to the adaptation illustrated in Fig. 1, A indicates one of the railway tracks and 75 B the other track, track A, for example, being for east bound traffic and track B being for west bound traffic. H represents the highway crossing. W indicates the tripping switch for track A and is installed adjacent 80 one of the rails at a suitable distance west of the highway. X indicates the resetting switch for track A and is installed adjacent one of the rails at a suitable point relatively to the highway so as to be operated as or 85 after the dangerous condition of the crossing is relieved. Both switches W and X are operated by the wheels of a passing train or railway vehicle. In like manner Y is the tripping switch for track B and is installed 90 adjacent the track for operation by the passing train at a suitable point east of highway H, and Z is the resetting switch for said track and is installed adjacent the track at a suitable point relatively to the highway 95 similarly to switch X. S indicates the signal suitably mounted in housing T adjacent highway H where it will be visible to travelers on the highway approaching the crossing from either direction. The signal may 100 be made in any suitable or desirable form, but preferably it carries electric lamps or other light giving means by which the signal will be illuminated for night use.

I contemplate supplying electrical current 105 for operating a number of signals from a single source, the current being carried by suitable feed wires, or by a single

feed wire with ground return. In the drawings I show a single feed wire 1 the return of the electrical current to the source being through the ground. Each of the 5 tripping switches W and Y has a connection to feed wire 1, the feed wire being also tapped at a third point for supplying electrical current for operating the signal mechanism upon the operation of either of 10 the tripping switches by a passing train or railway vehicle. Wire 2 is connected to the feed wire and to fuse or other circuit breaker 3 and wire 4 is connected to the fuse and to contact 5 of switch W. Contact 5^a 15 of the switch is connected by wires 7, 8 and 9 to magnet yoke 10 of holding magnet 11. Bar 6 normally closes the circuit between contacts 5 and 5^a and is adapted to be disconnected therefrom by a passing train or 20 vehicle which operation of the switch also connects bar 12^c to contacts 12 and 12^a, contact 12 being connected to ground at 12^b and contact 12^a being connected to wire 8.

Shaft 10^a is revolvably supported by yoke 25 10 and rigidly carries hook 13 and armature 14. Armature 14^a is loosely supported on the shaft and has movement thereon independently of armature 14 and in a recess formed within the latter armature. 30 Both armatures 14 and 14^a are attracted by holding magnet 11 when the latter is energized. They may be formed in one piece but I prefer them to be separate in order that the action of armature 15 rigidly secured to armature 14^a shall be rapid. A 35 flexible bonding conductor 10^b (Fig. 9) is secured to armature 15 and to yoke 10.

Hook 13 is adapted to engage arm 16 pivoted to arm 17 of weight 18, arm 16 40 having a counter-balance 16^c at its opposite end. A similar arm 16^a is also pivoted to arm 17 and is adapted to be engaged by hook 24 rigidly secured to shaft 21 revolvably mounted in yoke 22 of holding magnet 23. Arm 19 of weight 18 is rigidly secured to hub 20^a of signal S, the hub being revolvably mounted on shaft 20 projecting from the housing or within the housing. Weight 18 overbalances the signal 45 so that when hooks 13 and 24 are released, or either of them is released, the weight will descend and cause the signal to rise to danger or warning position.

Holding magnet 23 is controlled by tripping switch Y and it is adapted to attract armatures 25 and 25^a, armature 25 being rigidly secured to shaft 21 and armature 25^a being loosely supported on said shaft and rigidly connected to armature 26 and adapted 50 to operate in a recess formed within armature 25 independently of the latter armature for rapidity of movement of armature 26. Armature 26 is connected to yoke 22 by a flexible bonding conductor 22^b 55 (Fig. 9). Wire 65 is connected to magnet

yoke 22 of holding magnet 23 and to wire 52, the latter wire being connected to contact 62^b of tripping switch Y, contact 62 of said switch being connected by wire 63 to fuse or other circuit breaker 63^a and the 70 fuse having a connection to feed wire 1. Bar 62^a normally closes the circuit between contacts 62 and 62^b. Contact 62^d of switch Y is connected to ground at 66 and contact 62^c is connected to wire 52. Bar 62^e is 75 adapted to close the circuit between contacts 62^c and 62^d when the switch is operated by a passing train or railway vehicle.

Holding magnet 11 is connected by wire 27 to contact lug 28 and to holding magnet 23 by wire 29, wire 30 being connected to wire 29 and to binding post 31 grounded at 31^a. Wire 35 is connected to holding coil 23 and to contact lug 36. Contact lugs 28 and 28^a are adapted to be abutted by armature 15 and contact lugs 36 and 36^a are adapted to be abutted by armature 26. Contact lugs 28^a and 36^a are connected to wire 38 connected to winding 33^a of magnet 34, said winding being connected to wire 68 90 connected to switch 67, wire 64 being connected to contact 67^a of said switch and to fuse 69, the fuse being connected by wire 70 to feed wire 1.

Wire 41 is connected to binding post 31 95 and to solenoid 42 and wire 43 is connected to the solenoid and to switch 44, wire 44^b being connected to contact 44^a of said switch and to wire 55 connected to contact 56 of the bell controlling switch P. Bell 100 59 is connected to contact 56^a of switch P and to ground at 60. Wire 55 is also connected to contact 73 adapted to be abutted by contact 72^a on armature 72 pivotally supported on yoke 33 of magnet 34, the 105 yoke being connected by wire 71 to wire 68. Contact 73 is connected by wire 74 to winding 33^b of magnet 34.

Spring 44^c is connected at one end to switch arm 44 and at its other end to lug 110 20^a projecting from hub 20 of signal S and is adapted to move the switch arm 44 away from and to contact 44^a as signal S descends or rises.

Arm 57^a is adapted to close the circuit between contacts 56 and 56^a of switch P, said arm being carried by bar 57^a, pivotally supported at 57^m to the housing. Link 57^f is connected to pivot 57^m and is also pivotally connected to link 57^c. Spring 57 is connected at one end to the lower end of link 57^c and at its other end to substantially the center of bar 57^a. The opposite end of link 57^c is pivotally connected to a Y member 57^d pivoted to the housing at 57^p. Bar 57^h 125 is also pivoted at 57^p and carries arm 57^h adapted to close the circuit between contact 57^k and terminal 57^l. Spring 57^g is connected to substantially the center of bar 57^h and to the Y member. Terminal 57^l 130

and contact 57^k are connected by wires 61 and 61^a to lamps *t* and *t'* in signal S (Fig. 8) through which electrical current is supplied to the lamps to illuminate the signal. 5 when switch arm 57ⁱ is closed on contacts 57^j and 57^k. The lamp controlling switch, designated as an entirety by Q, is therefore operated simultaneously with the bell controlling switch P and the operation is effected 10 by a laterally projecting pin on arm 17, preferably the projecting end of the pivot 16^x of arms 16 and 17. The downward movement of the pin as weight 18 descends, when released from hooks 13 and 24, engages 15 the Y member and rotates it downwardly on its pivot to move link 57^e downwardly and cause springs 57 and 57^e to close switches P and Q, the springs opening the switches as the pin rotates the Y member in the opposite direction as weight 18 in its ascent elevates the pin. Any form 20 of controlling switches and their arrangement and means of operation will suffice, switches P and Q and arrangement and 25 mode of operation being illustrative only.

Resetting magnet 39 is connected by wires 45 and 47 to contacts 46 and 46^a of resetting switch X, wire 47 being connected also to wires 8 and 9. Contact 46^b of switch X 30 is connected to ground and contact 46^c is connected by wire 51 to wire 45. Bar 46^d normally closes the circuit between contacts 46 and 46^a and bar 46^e is adapted to close the circuit between contacts 46^b and 46^c 35 when the switch is operated by a passing train. Resetting magnet 39 is, therefore, normally maintained inoperative by a shunt circuit controlled by the resetting switch X and comprising wire 45, contact 46, bar 40 46^d, contact 46^a and wire 47 to wire 8.

Resetting magnet 40 is connected by wires 48 and 49 to contacts 50^a and 50 of resetting switch Z, switchbar 50^d normally closing the circuit between said contacts to form 45 a shunt circuit for the magnet 40 similarly to the shunt circuit for magnet 39 and for a similar purpose. Contact 50^b of switch Z is connected to ground and contact 50^c is connected by wire 53 to wire 49. Switch 50 bar 50^e is adapted to close the circuit between contacts 50^b and 50^c when the switch is operated by a passing train or vehicle.

Binding post 31 is connected by wire 32 to winding 33^b of magnet 34 and wire 74 is 55 connected to said winding and to contact 73. A small portion of the electrical current supplied to contact 73 by the circuit including feed wire 1, wire 70, fuse 69, wire 64, switch 67, wires 68 and 71, magnet yoke 33, armature 72 and contact 73 is permitted to flow through wire 74, winding 33^b of magnet 34 and wire 32 to ground at the binding post; thereby energizing said magnet and maintaining armature 72 in engagement with contact 73. If for any reason

the feeder current is cut off or interrupted magnet winding 33^b will be deenergized releasing armature 72 which breaks the circuit to the solenoid at contact 73 and also the circuit to the bell or audible signal 59. 70 Armature 72 will remain in said disconnected position until one of the tripping switches is operated by an approaching train, at which time it will be reset by magnet 34, provided the feeder current has resumed its flow, and signal S will also remain in the position of danger and the audible signal will remain silent. When, for example, trip switch Y is operated, assuming that feeder current is again flowing, 75 armature 26 still being unlocked and engaging contact 36^a, the operation of the switch grounds it at 66. This causes current to flow from feed wire 1 through wire 70, fuse 69, wire 64, switch 67, wire 68, winding 33^a, 80 wires 38 and 37, contact 36^a, armature 26, yoke 22, wires 65 and 52, contact 62^c, bar 62^e, and contact 62^d to ground at 66. Winding 33^a is therefore energized to attract armature 72 and cause it to connect to contact 73 whereupon current flows from wire 68 through wire 71, yoke 33, armature 72, contact 73, wire 74, winding 33^b of magnet 34 and wire 32 to ground at binding post 31, current also flowing through wire 55 to 90 the bell or other audible signal 59. The current flowing through winding 33^b reenergizes the same and locks armature 72 on contact 73, and the entire mechanism is again operative.

Switch 67, opposed by spring 67^b, is intended to be used to break the circuit in case repairs are necessary to any part of the mechanism, or in case it is desired to cut-out the bell and the swinging of the signal independently of the track switches, as for example, when a train has come to a stop at the crossing and it is desired to stand there for some time. The operator merely opens the switch, the spring automatically returning it to closed position. The opening of the switch momentarily breaks the circuit at contact 67^a thereby causing magnet 34 to deenergize and release armature 72 to break the circuits to the signal reciprocating or oscillating mechanism and to the audible signal.

In operation, and assuming the various switches and mechanisms in the positions shown in Fig. 1, and a train approaching 110 the highway on track A. When the train reaches tripping switch W the front wheel on the first vehicle operates the switch, disconnecting bar 6 and connecting bar 12^c to contacts 12^a and 12. The circuit to holding magnet 11 is thereby broken at contacts 5 and 5^a, the magnet is deenergized and armatures 14 and 14^a descend by gravity to rotate shaft 10^a and cause hook 13 to disengage from head arm 16 and armature 15 to con- 115 120 125 130

nect to contact stud 28^a. Since head arms 16 and 16^a are pivotally connected to arm 17 of weight 18 arm 16^a readily slips off hook 24 under the influence of the weight which 5 now descends to elevate signal S. As the signal rises it causes switch 44 to close and the descending head arms or the pin on arm 17 heretofore described rotates Y member 57^a to cause controlling switches P and Q 10 to close. The contact of armature 15 and contact stud 28^a grounds at 12^b the circuit from feed wire 1, through wire 70, fuse 69, switch 67, wire 68, winding 33^a, wire 38, contact stud 28^a, armature 15, yoke 10, wires 9 15 and 8 and bar 12^c and a shunt circuit from contacts 12^a, bar 12^c, contact 12 to ground at 12^b is therefore established so that no stray current may enter the holding magnet 11.

When the signal causes switch 44 to close 20 on contact 44^a current flows from feed wire 1 through wire 70, fuse 69, switch 67, wire 68, wire 71, magnet yoke 33, armature 72, contact 73, wire 55 to the bell and through switch 44, wire 43, the solenoid and wire 41 25 to ground at the binding post 31. The current energizes the solenoid which thereupon attracts and elevates its armature 42^a and the armature elevates weight 18 and lowers the signal. The downward movement of the 30 signal disconnects switch 44 cutting off the current to the bell and to the solenoid so that the weight is again free to descend to elevate the signal and the operation is repeated over and over again until the train 35 meets and operates resetting switch X.

Lighting current for the lamps in the signal being supplied at contact 57^a and terminal 57^b the closing of switch Q by the rotation of the Y member caused by the descent of 40 weight 18, causes said current to illuminate the lamps and the signal at each descent of the weight, the lamps being extinguished at each ascent of the weight. The swinging of the signal arm and the intermittent illumination of the lamps and the intermittent ringing of the bell necessarily attract the attention of the traveler on the highway.

When the front wheel of the first vehicle 45 meets and operates resetting switch X^b arm 46^a is disconnected from contacts 46 and 46^a and bar 46^c is connected to contacts 46^b and 46^c so that switch X is now grounded. Current now flows from feed wire 1, through fuse 3, switch W, wires 7, 8 and 47, resetting 50 magnet 39, wires 45 and 51, bar 46^c to ground. The current therefore energizes magnet 39 and armature 15 is attracted to quickly disengage from contact lug 28^a and engage contact lug 28. Current then flows 55 from feed wire 1, through fuse 3 switch W, wires 7, 8 and 9, yoke 10, contact lug 28, wire 27, holding magnet 11, wires 29 and 30 to ground at binding post 31, and energizes the holding magnet to attract armature 14 60 and move hook 13 into position to engage 65

head arm 16. Upon the next ascent of weight 18 both head arms 16 and 16^a strike hooks 13 and 24 respectively and since the arms are pivoted independently they are depressed by the hooks and their extremities 70 pass above the engaging ends of the hooks. When the weight again descends the extremities of arms 16 and 16^a engage the said ends of the hooks respectively and since the weighted ends of the arms abut and prevent 75 all upward movement of the outer ends of the arms the hooks prevent farther downward movement of said arms and retain and support the weight, the signal being now in the down or safety position, in which position it will remain as long as holding magnets 11 and 23 continue to be energized.

If a train is approaching on track B the functions of switch Y, holding magnet 23, hook 24, switch Z and resetting magnet 40 80 and the other circuits and devices common to both tracks are performed in exactly similar manner to that just described, and it is therefore unnecessary to repeat them. In the event a train is approaching the highway 90 on each track the signal will be operated by each without interference by the other and it will remain in operation until both resetting switches have been operated and both resetting magnets energized.

In case no current is flowing in feed wire 1 holding magnets 11 and 23 will be deenergized and weight 18 will descend to elevate the signal S to the danger or warning position, the bell will be silent but the lamps in 100 the signal will be illuminated in the event an independent lighting current is supplied for the illumination of the lamps. If the current resumes its flow prior to the operation of a tripping switch the normal operation of the signal and bell will be resumed. The shunt circuits provided for the holding magnets and the resetting magnets prevent any stray current in the circuit operating any of those magnets, hence none of them 110 will be energized until it is desired that it shall be energized.

In the case of a single track, illustrated in Fig. 2, one holding magnet 11, one resetting magnet 39 and one resetting switch X 115 are necessary only. In other respects the devices and circuit connections therefor to operate the signal and the bell and illuminate the lamps in the signal are identical to those previously described. A single hook 120 13 is used and one head arm 16 is pivoted to arm 17 of the weight. A stop 17^a on arm 17 limits the upward movement of arm 16. The tripping switches W and Y are connected in series in the following circuit: 125 from feed wire 1 through fuse 63^a, wire 63, contact 62, bar 62^a, contact 62^b wire 75, contact 5, bar 6, contact 5^a, wires 8 and 9, yoke 10, armature 15, contact stud 28, wire 27, holding magnet 11 and wire 30^a to ground 130

at binding post 31, bar 62^a of switch Y and bar 6 of switch W being assumed to be in their normal positions. The operation of either switch W or Y breaks the said circuit and causes the holding magnet to be deenergized to permit the signal to operate as before described.

In the present illustration it is essential that there shall be means at each tripping switch for neutralizing the effect of the operation of said switch by a train which has passed the highway crossing otherwise a passing train would operate the tripping switch on the opposite side of the crossing and there would be nothing to reset the mechanism and stop the operation of the signal arm. In Fig. 2 I have shown one means of neutralizing the operation of each tripping switch so that after the resetting switch has been operated by a passing train the subsequent operation of the tripping switch on the far side of the highway crossing will have no effect on the signal operating mechanism. I install adjacent switches W and Y switches M and N respectively. Contact 77 of switch M being connected by wire 12^a to contact 12 of switch W, contact 77^a being connected by wire 77^c to wire 8, contact 77^b to wire 75 by wire 77^f, and contact 77^d connected to ground. Bar 77^e normally connects contacts 77 and 77^a so that contact 12 of switch W is normally grounded at contact 77^d, and bar 77^c is adapted by the operation of the switch to connect contacts 77^a and 77^b. Similarly contact 76 of switch N is connected to 62^d of switch Y by wire 62^e, contact 76^a is grounded, contact 76^c is connected by wire 62^f to wire 63, contact 76^d is connected by wire 62^g to wire 75, bar 76^b normally connects contacts 76 and 76^a so that contact 62^d of switch Y is normally grounded at contact 76^a and bar 76^c is adapted to connect contacts 76^e and 76^d when switch N is operated. A train approaching switch W from the right in Fig. 2, will first operate switch M to break the ground connection and connect wires 8 and 75 to contacts 77^a and 77^b so that current will flow from feed wire 1 through switch Y, wire 75, bar 77^c, wires 8 and 9, yoke 10, armature 15, contact stud 28, through the holding magnet to ground at binding post 31. The train then operates switch W to open the circuit at contacts 5 and 5^a and closing bar 12^e on contacts 12 and 12^a; but the opening of the circuit by switch W has no effect on the holding magnet since switch M has closed the said circuit, and as switch M is slower in its return to normal position than switch W, as hereafter explained, switch M will maintain the closure of said circuit until switch W has returned to normal position following the passage of the last wheel of the vehicle or train. Switches N and Y operate in similar manner.

Resetting switch X is in a normally open circuit extending from wire 8, through magnet 39, wires 45 and 51 to contact 46^c, bar 46^e being adapted to be connected to contacts 46^e and 46^b by the operation of the switch for closing the said circuit and causing current to flow from feed wire 1, through switches Y and W, wire 8, resetting magnet 39 and wires 45 and 51 to ground at contact 46^b and thereby energize the resetting magnet to attract armature 15 and close the circuit through holding magnet 11.

Any suitable means for counteracting the effect of the operation of the tripping switches after a passing train has passed the highway will suffice, the switches M and N being illustrative only of one such means.

In both adaptations of the invention illustrated in Figs. 1 and 2, if for any reason whatever current fails to flow through the holding magnet only the signal is immediately released and will be moved up and down, the audible signal sounded and the signal will be illuminated intermittently as before described until a resetting switch is operated to close the circuit to the holding magnet. Any stray current in any circuit will not affect either the holding magnets or the resetting magnets when the holding magnet has been deenergized by the failure of current or by the operation of a tripping switch. Hence the signal will at all times indicate danger unless a holding magnet is energized by electrical current flowing from the feed wire.

In Figs. 3 and 4 I illustrate a form of tripping switch which is well adapted to control a holding magnet. It consists of housing or box B adapted to be installed adjacent a rail R of the track, the cover B' being removably secured to the box. Shaft 80 is revolubly supported in packing nuts 80^a and 80^b in threaded engagement with the wall of box B and boss 80^c, the opposite end of the shaft being revolubly supported by bearing post 80^d. One end of the shaft projects exteriorly of the box and one end of lever 81 is rigidly secured to the projecting end of the shaft. The lever extends toward rail R, its free end rigidly supporting bearing pin 82 and the pin rigidly supporting the free end of lever 83 rigidly secured to the projecting end of shaft 84. Roller 82^a is revolubly supported on bearing pin 82 and is adapted to be engaged by the wheels of a train or vehicle on rail R, the engagement of the same depressing the roller and levers to cause shafts 80 and 84 to rock clockwise (Fig. 4). Shaft 84 is revolubly supported in bearing post 84^a and in packing nuts 84^b and 84^c in threaded engagement with boss 84^d and the wall of box B.

Weight 85 is secured to shaft 80, an extension 85^a on the opposite side of the shaft being pivotally connected to the upper por-

100

105

110

115

120

125

130

tion of dash cup 86, the lower portion of said cup being pivoted on lug 86^a projecting upwardly from the bottom of box B. When lever 81 is depressed to rock shaft 80 weight 5 85 rises, the dash cup serving to cushion the return movement of the weight to avoid shock and also to control the return movement of the weight when pressure on the lever is released. The dash-cup is designed 10 to produce the required control of the descending movement of the weight, especially to control the time consumed in the said descent.

A curved lever 87 is rigidly secured to 15 shaft 84 and spring 87^a is secured at one end to the free end of the lever and at its other end the spring is secured to bar 87^b rigidly held between the arms of U-shaped member 88, the latter member being pivoted at the 20 extremities of its arms to posts 88^a and 88^b fixed in the box. A head 88^c is secured to the central portion of the U-shaped member and connecting bars 89 and 90 are hinged to the upper and lower faces of the head respectively but electrically insulated therefrom. A block 91 of insulating material is secured to lug 91^a projecting from a wall of the box and its opposite end is secured to an extension formed on bearing post 84^a. Contacts 92 and 93 are carried by block 91 and 25 are adapted to be engaged by connecting bar 89 in the normal unoperated position of the switch. A second insulating block 91^b is suitably secured below connecting bar 90 30 and carries contacts 94 and 95 which are adapted to be engaged by bar 90 when the switch is operated.

Conduit 96 is connected to the box at a suitable point through which the electrical 40 conductors 96^a and 96^b are admitted into the box, conductor 96^a being connected to contact 92 and conductor 96^b being connected to contact 93, the latter contact being connected by a suitable conductor to contact 94 and 45 contact 95 being connected by a wire 95^a to binding post 95^b on the wall of the box, the box being grounded to rail R. Any suitable manner of grounding contact 95 will suffice. Comparing Figs. 3 and 4 with switch W of 50 Fig. 1, for example, contact 92 corresponds to contact 5 of Fig. 1; contact 93 to contact 5^a; bar 89 to bar 6; contact 94 to contact 12^a and contact 95 to contact 12 and bar 90 to bar 12^c.

55 The operation of the switch is apparent, but briefly stated when a wheel of a train meets roller 82^a it depresses the roller and the levers causing shafts 80 and 84 to rock clockwise and elevate the weight and lower lever 87. As lever 87 descends it pulls on spring 87^a and as the line of action of the spring passes the pivotal axis of U-shaped member 88 the member will be drawn downwardly by the spring carrying with it head 60 88^c and connecting bars 89 and 90. Bar 89

is, therefore, disconnected from contacts 92 and 93 and bar 90 is connected to contacts 94 and 95. The release of the depressing pressure on lever 81 permits the weight to descend under the control of the dash-cup and lever 87 rises to disconnect bar 90 from contacts 94 and 95 and connect bar 89 to contacts 92 and 93 as before. Ordinarily 70 the several wheels of a train operate the levers in comparatively quick succession, but 75 unnecessary pounding of the roller and other parts of the switch is avoided by the dash-cup.

In Figs. 5 and 6 I illustrate a form of resetting switch adapted for use in my signaling system. The box B² is adapted to be installed adjacent rail R of the track, the cover being removable as in Fig. 4 and having a water tight joint *j* similar to the water tight joint *j* in Fig. 4. Shaft 102 is 80 revolvably mounted in packing nuts 110 removably secured in opposite walls of the box and in bosses 111. Lever 103 is rigidly secured at opposite ends to the projecting ends of shaft 102 and supports at its central point a bearing pin 104^a upon which roller 104 is revolvably mounted, the roller being adjacent the rail so that the wheels of a passing train or vehicle will abut and depress it and cause the lever to rock shaft 102 clockwise (Fig. 6). Arm 101^a is secured to the shaft and carries, preferably integrally therewith, weight 101, the arm being curved downwardly and rearwardly from the shaft. A lug 105 projects upwardly from the top of the weight and one end of spring 106 is 85 connected to the lug, the opposite end of the spring being secured to bar 112 rigidly carried by U-shaped member 113 pivotally connected to posts 114 and 114^a, the U-shaped member carrying head 115 to the top and bottom faces of which connecting bars 117 and 116 are hinged respectively. Bar 116 90 normally engages contacts 118 and 119 carried by insulating block 130 supported by lugs 131 on the walls of the box and bar 117 95 is adapted to engage contacts 120 and 121 carried by insulating block 122.

The upper section of dash cup 107 is pivotally supported by lug 109 and the lower section is pivotally connected to weight 101. Conduit 123 admits electrical conductors 124 and 125, conductor 124 being connected to contact 118 and conductor 125 being connected to contact 119, the latter contact being connected by conductor 126 to contact 121 and conductor 127 being connected to contact 120 and to the wall of the box.

When the wheel of a passing train abuts and depresses the roller and lever, the lever 125 causes shaft 102 to rock to elevate weight 101. Lug 105 is lifted and elevates one end of spring 106 to cause U-shaped member 113, head 115 and connecting bars 116 and 117 to elevate, bar 116 disconnecting from 130

its normal engagement with contacts 118 and 119, and bar 117 connecting to contacts 120 and 121. Conductors 124 and 125 are also connected to a resetting magnet (Figs. 5 1 or 2), and correspond to conductors 45 and 47 or 48 and 49 of Fig. 1. Since connecting bar 116 normally engages contacts 118 and 119, if any of the various parts or electrical circuits of the switch or system 10 are broken the bar will not be disturbed but will maintain the shunt circuit for the resetting magnet heretofore described, and the signal will remain in the position of danger or warning, if the signal has been operated 15 previously to take that position. And in the tripping switch illustrated in Figs. 3 and 4 connecting bar 89 normally engages contacts 92 and 93 and is maintained in that position by weight 85. The breaking of any 20 of the mechanical parts between the weight and head 88^c will release the head and it will drop by gravity carrying with it connecting bars 89 and 90 to break the connection between contacts 92 and 93 (contacts 25 5 and 5^a, Fig. 1) and cause the holding magnet to be deenergized to set the signal in the danger or warning position.

It is apparent that by my system any failure of electrical current to flow in all the 30 circuits or the breakage of any of the switches, except the resetting switch mechanism, will cause the signal to assume automatically the danger position, and that when the current does fail its resumption of 35 flow will not cause the signal to drop to safety position unless a tripping switch and a resetting switch are operated. Hence the system is positive and all parts and circuits must be in working order to cause the 40 signal to indicate a safe crossing.

Fig. 7 is a modified form of actuating lever for either the tripping or resetting switch in which the lever is operative in only one direction. The mechanical cut-out device 45 will be substituted for the tread or roller 82^a or roller 104 of Figs. 3 and 5 respectively. Referring to Fig. 7, U represents the U-shaped bar or lever connected to the shafts 80 and 84 Fig. 3 or to shaft 102 Fig. 50 5, a lug or pin P' projecting laterally from the side of the bar facing rail R. Rocker arm R' is pivoted at S' to the bar U its lower end W' being weighted to hold the arm in vertical position normally. The upper end arm R' carries roller O which is adapted to be abutted by the wheel of a 55 passing train for rocking the arm on pivot S'. When the wheel of a train abuts roller O on the right side, (Fig. 7), arm R' is 60 rocked to the left and abuts pin P'. The continued movement of the arm by the wheel depresses bar U and operates the switch mechanism. When a wheel abuts the roller on its left side (Fig. 7) the arm is rocked to 65 the right to a horizontal position but with-

out depressing the bar U, there being no pin P' on the portion of the bar to the right of pivot S'.

Various modifications in the construction and arrangement of the parts and electrical 70 circuits will be obvious to those skilled in the art. Various means may be adopted for conveying electrical current from the feed wire to the tripping switches and to the signal mechanism; but I believe all such 75 modifications will be within the scope of my invention.

What I claim is:

1. In an electric signaling system, means to hold the signal in non-operated position, 80 an electro-magnet to control the said means and being in a normally closed circuit, a switch to control the electro-magnet, a shunt circuit for the electro-magnet controlled by said switch, the deenergizing of the electro-magnet releasing the holding means to permit the signal to automatically move to operated position, an electro-magnet adapted to reset the holding means and being in a normally shunted circuit, and a switch to 85 control the latter electro-magnet and said shunt circuit.

2. In an electric signaling system, a signal, mechanism to hold the signal in non-operated position, an electro-magnet adapted when energized to retain the holding mechanism in engagement with the signal, an electrical circuit for the electro-magnet, a switch normally closing the said circuit and adapted when operated to break the 100 said circuit and to establish a shunt circuit for the electro-magnet, for deenergizing the electro-magnet, an electro-magnet in a normally open circuit adapted to reestablish the first named electric circuit to the first 105 named electro-magnet for resetting the holding mechanism, a shunt circuit for said resetting electro-magnet and a switch to control the latter electro-magnet and its shunt circuit, the signal being adapted 110 to move to operated position automatically upon the cessation of flow of electrical current to the first named electro-magnet.

3. In an electric signaling system, a signal, electrically actuated means to hold the 115 signal in non-operated position, the said means being adapted to release the signal whenever electrical current fails to flow to the same whereupon the signal moves to operated position, electrically actuated means 120 to reset the holding means, a switch to control the same, and a switch to control the first named electrically actuated means comprising a pair of contacts in circuit between the first named electro-magnet and a source 125 of electrical energy, a contacting member adapted to complete the said circuit between said contacts, means normally holding the contacting member in engagement with said contacts and adapted to automatically re- 130

store said engagement after the operation of said switch, the said means being so connected to said contacting member that the breakage of any part of the said connections causes the said contacting member to break its engagement with said contacts.

4. In an electric signaling system the combination with a signal and electrically actuated means to hold it in non-operated position, of a tripping switch adapted to break the flow of electrical current to said means and comprising a contacting element, two contacts adapted to be normally engaged by said contacting element for normally closing the electrical circuit to said means, a weight, means connecting the weight and contacting member and adapted by the operation of the switch to break the normal engagement of the contacting member and said contacts the said weight tending to maintain said normal engagement, the said connecting means being so arranged that should any part of it break the contacting member will automatically break its connection with said contacts.

5. In an electric signaling system the combination with a signal and electrically actuated means to hold it in non-operated position, of an electrical circuit for said means and a tripping switch in said circuit adapted by its operation to open said circuit and comprising two contacts in said circuit, a contacting element to close the circuit between said contacts, a rock shaft having a connection to the contacting element and adapted by its rotation to break the engagement of the contacting element and said contacts, means to rotate the rock shaft, and means having a connection to the rock shaft and adapted to normally engage the contacting element on said contacts, the connections between said latter means and said contacting element being such that in case of breakage of any part thereof the said contacting element automatically breaks its engagement with said contacts.

6. In an electric signaling system the combination with a signal and electrically actuated means to hold it in non-operated position, of an electrical circuit for said means and a tripping switch in said circuit adapted by its operation to open said circuit and comprising two contacts, a contacting element adapted to engage the contacts to close said circuit between said contacts, a pivotally mounted support for the contacting ele-

ment, a rock shaft having a connection to the support, a second rock shaft having a connection to the first named rock shaft, a weight secured to the second rock shaft and adapted normally to cause the contacting element to engage the contacts, the several connections between the weight and said contacting element being such that in the event of breakage of any part thereof the said contacting element automatically opens the said circuit at said contacts.

7. In an electric signaling system the combination with a signal and electrically actuated means to hold it in non-operated position, an electrical circuit for said means, means normally closing said circuit and adapted to open the same for releasing the signal holding means, electrically actuated means for resetting the signal holding means, an electrical circuit for the latter means, a resetting means in the latter circuit normally opening the same and adapted to close it; a shunt circuit for the resetting means comprising two contacts in said circuit, a contacting element normally engaging the contacts by which the said circuit is closed and means having a connection to the contacting element adapted to disconnect it from said contacts, the said connecting parts being so arranged that in the event of breakage of any of the same the said contacting element remains in contact with said contacts.

8. In an electric signaling system, a signal, and electrically actuated means for holding the signal in non-operated position, a normally closed circuit for said means, a tripping switch in said circuit adapted to open the same for deenergizing the holding means and permitting the signal to move to operated position, electrically actuated means to cause the signal to oscillate when released, means to illuminate the signal, an audible signal, means to control the illumination of the signal and the audible signal and means to cut out the operation of the audible signal and the oscillation of the signal controlled by an electro-magnet having holding and resetting windings thereon, the resetting of said cut out mechanism being controlled by said tripping switch.

In witness whereof I have hereunto set my hand this 18th day of February, 1919.

HUGH D. MURPHY.
